(57) **CLAIM**

The ornamental design for an anti-rat flap as shown.

DESCRIPTION

FIG. 1 is a front perspective view of a first variant of the anti-rat flap;

FIG. 2 is a front elevation view of the anti-rat flap of FIG. 1;

FIG. 3 is a rear elevation view of the anti-rat flap of FIG. 1; FIG. 4 is a left-side elevation view of the anti-rat flap of FIG. 1;

FIG. 5 is a right-side elevation view of the anti-rat flap of FIG. 1;

FIG. 6 is a top plan view of the anti-rat flap of FIG. 1; and, FIG. 7 is a bottom plan view of the anti-rat flap of FIG. 1. The broken lines shown on the drawings depict portions of the anti-rat flap that form no part of the claimed design.

1 Claim, 5 Drawing Sheets
